UNITED STATES PATENT OFFICE

CLAI'RE KURTZ, OF BALDWIN, NEW YORK

DESIGN FOR A DRESS

Application filed December 28, 1931. Serial No. 42,261. Term of patent 3½ years.

To all whom it may concern:

Be it known that I, CLAI'RE KURTZ, a citizen of the United States, and a resident of Baldwin, in the county of Nassau and State of New York, have invented the new, original, and ornamental Design for a Dress, of which the following is a specification.

Reference is had to the accompanying drawings, forming part thereof, wherein—

I claim:

The ornamental design for a dress substantially as shown.

CLAI'RE KURTZ.
